UNITED STATES PATENT OFFICE

FRANK ALESSI, OF BROOKLYN, NEW YORK, ASSIGNOR TO VINCENZO NAVA, OF BROOKLYN, NEW YORK

DESIGN FOR A COMBINED AIRPLANE AND THERMOMETER

Application filed January 3, 1930. Serial No. 34,014. Term of patent 14 years.

To all whom it may concern:

Be it known that I, FRANK ALESSI, a citizen of the United States, and a resident of Brooklyn in the county of Kings and State of New York, have invented the new, original, and ornamental Design for Combined Airplane and Thermometer, of which the following is a specification.

Reference is had to the accompanying drawing, in which—

Figure 1, is a perspective view of a combined airplane and thermometer, showing my new design.

Fig. 2, is an end view.

I claim:

The ornamental design for a combined airplane and thermometer, substantially as shown.

FRANK ALESSI.
